CLAIM

The ornamental design for a tillage ripper point, as shown and described.

DESCRIPTION

FIG. 1 is a front perspective view of a tillage ripper point according to our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a rear perspective view thereof;

FIG. 7 is a rear perspective view thereof;

FIG. 8 is lower rear perspective view thereof;

FIG. 9 is a left side elevation view thereof; and,

FIG. 10 is a right side elevation view thereof.

The ornamental design which is claimed is shown in solid lines in the drawings. The portions of the design shown in broken lines, dotted lines, or dashed lines, if any, illustrate portions of the tillage ripper point or are included for the purpose of illustrating environment and form no part of the claimed design. However, Applicant reserves the right to incorporate any one or more unclaimed feature(s), in whole or in part, into the claimed design. Moreover, Applicant reserves the right to disclaim any one or more feature(s), in whole or in part, of the claimed design as originally filed.

1 Claim, 6 Drawing Sheets
